RICHARD HOCHSCHILD, OF BARMEN, GERMANY, ASSIGNOR TO THE FIRM AUG.
SCHMIDTMANN, OF BARMEN, GERMANY

CARD UNIT FOR VISIBLE CARD SYSTEMS

Application filed August 8, 1928, Serial No. 298,292, and in Germany February 17, 1928.

The invention relates to card-units, and especially to index cards or holder-cards, for visible card-systems, in which the card proper and a guide and spacing strip flexibly joined therewith, are made to consist of one piece. It is already known in conjunction with cards of this description to bend the guide-strip Z-shaped for the purpose of forming a fold or a pocket to receive the guide-strip of an adjacent card. With these known cards the parts of the Z-shaped bent guide-strip are exclusively connected with each other at the point of bending, the connection being of such nature, that the strip-parts are forced apart owing to the elasticity of the card material. The natural consequence thereof is, that the free edge of the guide-strip is pressed down closely upon the baseplate of the card-index or card-system owing to the elastic action. This fact, however, as a matter of course, renders the introduction of the guide-strip into the fold of the neighbouring card more difficult and together with it the placing of the cards so as to form a straight pile. The result thereof is that, when sliding the cards into one another, it will be impossible for the free edge of the guide-strip to glide immediately into the fold of the neighbouring card, but will be caused to come in contact with the lower edge of this fold, or it may even happen that it is made to glide below the guide-strip of the neighbouring card. For this reason the free edge of the strip requires to be bent up by a special manipulation, so as to render it possible to pass it into the fold at all. This, as a matter of course, makes the formation of a straight row of cards a difficult and troublesome matter, which also applies to the subsequent insertion of cards in the row. To this must be added, that the free edge of the guide-strip, formed by the projecting single thickness of the strip blank is easily bruised, squashed or dented by the contact with the lower edge of the fold which is considerably stronger, which will still further render the introduction into the fold a matter of difficulty.

In the card representing the object of the present invention these defects have been obviated by folding a part of the card-blank adjoining the free edge of the strip-part towards the middle of the strip in such a manner, that it is caused to overlap the repeatedly folded part adjoining the card proper, and by firmly connecting the two strip-parts with each other at the point of overlapping, as for instance, by pasting. With this arrangement the free edge of the guide-strip is no longer pressed down elastically upon the base-plate of the index, but is capable of being freely moved up and down within the limits set by the guiding-grooves with which the base-plate of the visible card-system has been provided. This so facilitates the introduction of the free edge of the guide-strip into the fold of the neighbouring strip that this introduction, when pushing the cards together, is effected automatically so to speak. If, for instance, when pushing the cards together, the card, the guide-strip of which is to be made to engage in the fold of the neighbouring card, is held in a position as nearly parallel as possible to the base-plate, then the free edge of the guide-strip will be made to lift itself up so far from the base-plate, that it can pass into the fold of the neighboring card with ease. A contact with the lower edge of the fold of the neighbouring card can only then take place, if the card to be introduced is held in a position deviating from that referred to, or in other words, if the card is held in a position pointing upwards. In this case, however, nothing else is required but to turn down the card in order to remove the hindrance and to be able to introduce the guide-strip into the fold without any further manipulations. In conjunction with the new card, the formation of a row of the cards, as well as the subsequent introduction of cards into the row has been rendered especially easy and convenient. To this must be added the most essential advantage, that the guide-strip has been doubled along the whole of its width, and that, in particular, the free edge of the guide-strip, too, has been reinforced by folding or doubling, with the result, that a damage of this edge in any shape or form has been entirely obviated. The new card, therefore, possesses a considerably greater durability

50 100

than the known card with Z-shaped folded guide-strip.

The guide-strip of the new visible card-system may be reinforced and stiffened, if necessary, by means of an embedded strip of sheet-metal. The durability, on the one hand, has thereby been enhanced, and on the other hand it has been made certain that the guide-strip cannot curl, but always maintains the desired flat or stretched position required for the introduction into the fold of the guide-strip of the neighbouring card. The strip of sheet-metal embedded in the guide-strip may itself be stiffened by providing it with a longitudinal strengthening rib or equivalent reinforcing means.

The drawing represents in Figs. 1-5 one embodiment of the invention, in which

Fig. 1 illustrates a plan-view of the new card,

Fig. 2 a lateral view thereof,

Fig. 3 a sectional perspective view of the card on an enlarged scale,

Fig. 4 a plan-view of the blank not folded.

Fig. 5 is a sectional perspective view of a portion of the same partly folded,

Figs. 6 and 7 represent a modified form of the invention, in which

Fig. 6 shows a cross-section on an enlarged scale and

Fig. 7 a plan-view on a reduced scale, whereby the guide-strip in the lower half of the figure has been unfolded, for the purpose of exposing the insertion to view.

Fig. 8, finally, illustrates another modified form of the invention in cross-section on an enlarged scale.

A is a holder-card proper, provided with holding slits *a* or other suitable means for receiving portions of one or more index or like cards to be secured to said holder card, whilst B is the guide-strip, flexibly connected to and projecting on either side of the card proper. The card A and the strip B consist of one piece and are made from a single correspondingly stamped sheet of card-board as per Figures 4 and 5. The one part A of this sheet of card-board represents the card proper, the other part B¹ the blank for the guide-strip B. The joint C of the two parts is provided with a row of small holes 1 placed at certain intervals from each other, or it may also be rendered flexible in any other way, so as to form a hinge upon which the card A may be turned over. Whilst the portion A of the blank possesses the correct dimensions from the very beginning, the strip-blank B¹ only coincides in its length with the length of the complete guide-strip B, whereas its width is somewhat in excess, the width of the strip-blank B¹ being about two and one half or three times the desired width of the guide-strip B. The strip-blank B¹ is subdivided by two longitudinal bending-lines 2, 3 into a middle-part 4 and three lat-

eral parts 5, 6, 6^a, of which the lateral parts 6, 6^a adjacent the card-blank A¹ are joined together at another longitudinal bending line 7. For the purpose of forming the guide-strip B, the lateral parts 6, 6^a of the strip-blank adjoining the card A are in the first instance folded toward the middle of the guide-strip on the line 3. In connection herewith, however, only the part 6 is turned down upon the middle part 4 of the strip-blank, whereas the other part 6^a is folded back again at the line 7 in such a manner, that the parts 6, 6^a form a fold. Subsequently the lateral part 5 adjoining the free edge of the strip-blank is likewise folded down towards the middle and upon the middle-part 4, whereby this part 5 is made to overlap the lateral part 6^a. The two lateral parts 5 and 6^a are then firmly connected with each other at the point of overlapping, most suitably by being pasted together. The parts of the lateral strips 5 and 6 resting upon the middle part 4 may also suitably be pasted to the middle-part, which, however, is not absolutely necessary.

The fold between parts 6, 6^a serves, as is well known, for engaging the guide-strip of the neighbouring card. When assembling the cards, i. e. composing a plurality of cards so as to form a row, it is always the free edge of the guide-strip of the one card that is slid into the fold of the guide-strip of the neighbouring card, with the result, that the cards are displaced to each other by the distance between the free edge and the inside of the apex of the fold of a guide strip, i. e. put up in echelon order.

The four corners of the strip-blank B¹ may, as shown in Fig. 4, be cut off obliquely, with the result that the end edges of the upper wall 6 of the fold are caused to take a somewhat diagonal course, whereby projecting corners, which are liable to bend and subsequently may impede the sliding in of the guide-strip of the neighbouring card into the fold, will be avoided. There is, however, no necessity for chamfering the corners.

In the embodiments in Figs. 6 and 7 the guide-strip B folded in the same way as in the modification in Figs. 1-5, has been provided with a strip of sheet-metal 10 entirely embedded in the former, the length and width of which essentially coincides with the length and width of the guide-strip. The strip of sheet-metal serves for reinforcing and stiffening of the guide-strip B. The strip of sheet-metal itself is stiffened by means of a stamped-in longitudinal rib 11 suitably provided, as shown in the drawing, on the upper side of the metal-strip. The strip of sheet-metal 10 is advantageously pasted together with those parts of the guide-strip B which surround it.

In the modification in Fig. 8 the guide-strip B has also been provided with a strip

of sheet-metal embedded therein. The difference consists therein, that the metal-strip 10 shows a fold instead of a longitudinal rib. In connection herewith the longitudinal edge 5 12 of the folded-over portion of the strip of sheet-metal is turned round that fold of the guide-strip B which is overlapped by the lateral part 5 of the strip-blank.

It is obvious that within the range of this 10 invention modifications of the examples shown will be possible.

Instead of serving as holder-card (i. e. intended for holding the separate record cards in position) the card A itself may constitute 15 the record card. In this case the card is to be made from a material on which it is possible to write, and it therefore requires no special means for holding other cards.

Claims:

- 20 1. An index card or card holder for visible card filing systems or indexes having at one end a multifolded guide strip folded so as to present a bottom ply coextensive in length and width with the strip, a top ply, an intermediate ply joining said top ply with one longitudinal edge of the bottom ply and extending under said top ply toward the card body and forming with said top ply a pocket for the guide strip of an adjacent card, and a 25 intermediate ply joined to the other longitudinal edge of the bottom ply and extending over upon and secured to the said top ply of the strip.
2. Card, in accordance with claim 1, characterized in that the guide-strip is provided 30 with a metallic reinforcement enclosed therein.
3. Card, in accordance with claim 1, characterized in that the guide strip is provided with a reinforcement of sheet-metal enclosed 35 therein.
4. Card, in accordance with claim 1 wherein in the guide strip is provided with a metallic reinforcing plate enclosed therein, said plate having a strengthening rib.
- 45 5. An index card or card holder of the character set forth in claim 1 wherein the top ply of the guide strip is joined to the card body by a perforated weakened line.
6. An index card or card holder for visible 50 card filing systems or indexes having at one end a multifolded guide strip, said strip embodying a unitary bottom ply, overlapping top plies united to each other, and an intermediate ply forming with one of said top plies a card-receiving pocket.

In testimony whereof I affix my signature.
RICHARD HOCHSCHILD.
